UNITED STATES PATENT OFFICE.

MARTIN M. CODY, OF CHICAGO, ILLINOIS, ASSIGNOR TO CRANE PACKING COMPANY, A CORPORATION OF ILLINOIS.

MANUFACTURE OF METALLIC PACKING.

Application filed August 4, 1924. Serial No. 730,043.

My invention relates to improvements in the manufacture of metallic packing.

The objects of the invention are to provide an improved machine and method for the manufacture of a metallic packing ring which may be readily deformed to adapt it to the recess in which it is confined when subjected to endwise pressure. Such a packing ring is disclosed in the Julian N. Walton

10 Patent No. 1,543,963, granted June 30, 1925.

Said ring is a continuous metallic packing ring presenting smooth walls and composed of superimposed layers or convolutions of metal formed of interfitting folds or plaits 15 whereby said ring is particularly adapted as a packing for the ends of condenser tubes.

A further object of the invention is to provide a machine for manufacturing such a product rapidly and accurately.

20 In the accompanying drawings one embodiment of the machine is illustrated, together with several forms of the product.

Fig. 1 is a side elevation of the machine.

Fig. 2 is a plan view thereof with some of 25 the parts removed.

Fig. 3 is a section on line 3—3, Fig. 1.

Fig. 4 is a detached plan view of a knife operating mechanism.

Fig. 5 is a section on line 5—5, Fig. 1.

30 Fig. 6 is an elevation of one of the shafts with its associated corrugated roller.

Fig. 7 is a partial plan view of the stripper and associated parts.

Fig. 8 is an elevation of part of the punch.

35 Fig. 9 is a side elevation of one of the rings immediately after being rolled.

Fig. 10 is an end view thereof.

Fig. 11 is a side elevation of said ring after a partial compression endwise.

40 Fig. 12 is an end view thereof.

Fig. 13 is a side elevation of the compressed ring.

Fig. 14 is an end view thereof, and

45 Fig. 15 is an enlarged sectional view of a finished ring.

Fig. 16 is an enlarged sectional elevation of a modified form of ring.

Fig. 17 is a view showing the method of assembling the metal foil and fabric.

50 The machine comprises a table 1 supported on suitable legs or standards 2. Power is applied to the driving shaft 3 carrying a sprocket 4 which in turn drives a chain 5 and a second sprocket 6 on a shaft 7.

55 The shaft 3 is the crank shaft of a power

press. A bevel gear 8 is mounted on shaft 7 and drives a second bevel gear 9 which rotates a vertical shaft 10. The shaft 10 carries a gear 11 meshing with a pinion 12. Below gear 11 is a second gear 13 mounted on the 60 said shaft 10, said gear meshing with gear 14 which in turn meshes with a gear 15. These two latter gears rotate shafts 16, 17, on which are mounted two feed rollers 18, 19. These rollers are friction fed rollers, 65 having preferably wooden surfaces. They feed a strip or strips of flexible packing material to the right, in the position shown in Fig. 2; said material being fed from either of two supply spools 20 or 21. While 70 one spool is being unwound, a full spool may be supplied in place of the one just emptied.

As the metal ribbon leaves spool 20, it passes along a sheet metal guide 22, being held against the same by a tension roller 23 75 mounted on an arm 24, being yieldingly pressed against the same by a spring (not shown). The ribbon then passes between the feed rollers 18, 19, being drawn smooth and flat between the tension roller and said feed rollers.

After passing the feed rollers, it is guided along to the corrugated winding rollers 25, 26, which grip the thin metal foil between them in such wise as to avoid slipping. The corrugated roller 25 (see Fig. 6) 80

is mounted on a shaft 27 having a pinion 28 thereon which is driven by gear 11. The corrugated roller 26 is mounted on an arm 29 pivoted at 30 and yieldingly held against roller 25 by an adjustable tension spring 31. 85

A guide 32 is provided which prevents the foil from winding about the corrugated roller 26, thereby insuring that it will wind about the corrugated roller 25 for the purpose of forming a ring composed of a number of turns and having a pre-determined length. The length is determined by the cutoff knife 33 mounted on the end of an arm 34 which in turn is secured to a shaft 35

90 having an upper arm 36 thereon carrying a roller 37 which is yieldingly held against a cam 38 mounted on the main vertical shaft 10. Cam 38 has a split hub 39 formed thereon carrying a stud 40 enabling said cam to be

95 clamped about the shaft in any desired position of adjustment. As the shaft rotates, the knife moves inwardly against the metal foil at different pre-determined intervals, thereby cutting off exact lengths of foil as

100 the latter is being wound into a ring about 105

110

115

the corrugated roller 25. In this manner a definite number of turns and a definite thickness of a ring are obtained. At the instant that the knife cuts the foil, the feed roller 19 swings away from the companion roller 18. This is effected by movement of the arm 41 which is secured to a shaft 42, the latter having an arm 43 near its upper end carrying a roller 44 which bears against a second cam 10 composed of two plates 45, 46, each having parts of its periphery cut away, as shown in Fig. 5; said plates being rotatably adjustable, one over the other, to provide a recess of variable length to control the timing of 15 the movement of the feed roller.

After a pre-determined length of foil has been rolled on the corrugated roller 25, it is stripped therefrom by being pushed downwardly by a sleeve 47 (see Fig. 6). Said 20 sleeve has an annular groove 48 at its upper end which is engaged by a forked arm 49 arranged at the lower end of a reciprocating rod 50 which is actuated by a pivoted arm 51 at the upper end thereof carrying a 25 roller 52 engaged by a cam 53 which is mounted on the horizontal shaft 7. A spring 54 tends to hold rod 50 and associated parts in uppermost position against the action of the cam. The sleeve 47 is keyed 30 to shaft 27 by means of a suitable key sliding in the slot 55.

The ring as thus far formed is corrugated, as shown in Figs. 9 and 10, showing an elevation and top plan view, respectively. As 35 it is pressed downwardly from the corrugated roller on which it is formed by collar 47, it is received within a collar of the die 56, of which there are twelve, mounted on a rotating plate or turret 57. This plate is 40 fed intermittently by means of a pawl 58 which engages a series of circumferential notches 59 in the turret.

The corrugated ring advances to the die in a step by step movement to a point beneath 45 the first punch 60, which is of well known construction, consisting of a reciprocating punch 61 and a collapsing pilot 62 yielding- 50 ly mounted therein. The head 60 is mounted on a transverse bar 63 which in turn is secured to a vertical reciprocating ram 64 55 sliding in guide-ways 65 in the frame of the press 66. The pilot enters the corrugated ring and the punch compresses the ring to about the relative size shown in Figs. 11 and 12. This compression of the ring causes the consecutive layers to assume a wavy V-shaped formation. After this operation, the rotation of the turret brings the die beneath the ram 64 where it is acted on by a second punch 67. Surrounding this punch is a stripper 68 having a groove 69 therein in which fits the end of a forked lever 70, the latter being pivoted, at 71, and held in lowermost position by a spring 72. 60 As ram 64 moves downwardly the ring is

compressed between the bottom of the die and the shoulder 73. The stripper 68 moves upwardly until it engages the shoulder of the punch after which spring 72 yields. The upward movement of the ram causes 70 the stripper to hold the ring in the die until the punch has been withdrawn, after which the stripper is also elevated. The relative size of the ring is now as shown in Figs. 13 and 14, the ring having been compressed and 75 compacted to the desired dimensions. Continued rotation of the turret brings the finished ring to the position indicated at 73 at which point a third arm (not shown) carrying a plug pushes the ring through the 80 platen of the press into a suitable receptacle. This plug or "kickout", as it is termed, is carried by the reciprocating ram 64 and is not shown as it is of standard construction. 85

In order to prevent the punch pilot, which performs the first pressing operation from carrying the partially compressed ring above the collar of the die, a stripper is provided comprising an arm 14. The latter is secured to a sliding carriage 75 on which pawl 58 is mounted. As the carriage reciprocates the arm 74 having a notched out part 76 engages the pilot 62 immediately above the collar of the die, thereby holding the ring 90 in the die as the pilot is drawn upwardly. The return movement of the carriage 75 causes the fixed arm 74 to travel to the right. 95

A modified form of packing is shown in Figs. 16 and 17 wherein a strip of metal foil 77 is folded over and a strip of fabric 78 is inserted within the folded metal strip. The fabric strip is preferably narrower than the folded metal strip so that the metal projects at each side beyond the fabric. The fabric 100 may be fed into the folded metal strip in previously cut lengths, the length of fabric corresponding to that necessary for a single ring. In the finished ring, as shown in Fig. 16, all faces are of metal, the fabric increasing 105 the resiliency of the finished ring after it has been compressed in dies. 110

What I claim is:—

1. A machine for making packing comprising a roll on which a strip of packing material is wound to form a ring, means for holding the material against said roll to avoid slip, means for cutting off a predetermined length of the material supplied to said roll, means for removing the wound ring from said roll, and means for compressing said ring. 115

2. A machine for making packing comprising a roll on which the packing is wound to form a corrugated ring, means for holding the material against said roll to avoid slip, means for removing the wound ring from said roll and means for compressing said ring axially. 120

3. A machine for making packing com- 130

- prising a roll on which the packing is wound, means for holding the forward end of the packing material against said roll to insure winding thereof without slip, means for cutting off a predetermined length of said material to insure a definite thickness of the packing ring, means for removing the wound ring from said roll, and means for compressing said ring in successive stages.
4. A machine for making packing comprising a corrugated roller, means for feeding a strip of soft metal to said roller, means for pressing said strip into the corrugations of said roller and causing it to wind itself thereon, a die, means for removing the packing from said roll and forcing it into said die, and means for compressing it within the die.
5. Apparatus of the class described comprising a roller, means for feeding a strip of packing material to said roller to be wound thereon to form an endless ring, a die, means for moving said ring from said roller into said die, and means for compressing the ring within the die.
6. Apparatus of the class described, comprising a roller, means for feeding a strip of packing material to said roller to be wound thereon to form an endless ring, a die, means for moving said ring from said roller to said die, means for compressing the ring within the die, and means for ejecting the compressed ring from said die.
7. A machine for making packing comprising a corrugated roller, means for feeding a strip of soft metal to said roller, means for pressing said strip into the corrugations of said roller, and causing it to wind itself thereon, means for cutting off a predetermined length of said strip to insure a predetermined thickness of the ring, means for removing said ring from said roller longitudinally and forcing it into a die, and means for compressing it within said die.
8. In a device of the class described, a pair of corrugated rollers, means for feeding a strip of soft metal foil between said rollers, one of said rollers pressing said foil into the corrugations on the other of said rollers and causing said foil to wind itself about said roller, means for stripping the wound ring from said roller, a rotatable turret having a plurality of openings therein arranged so that said rings are fed into the same, and means for compressing said rings in successive stages during the rotation of said turret.
9. In a device of the class described, a storage reel for a strip of soft flexible pack-
- ing material, a pair of feed rollers for drawing said material from said supply reel, a pair of corrugated rollers in engagement with each other, said feed rollers feeding said material to said corrugated rollers, whereby said material is wound about one of said corrugated rollers, a movable arm on which the other of said corrugated rollers is mounted, means for moving the latter roller from engagement with the former corrugated roller, and means for stripping the ring of material from said former roller.
10. In a device of the class described, a storage reel for a strip of soft flexible packing material, a pair of feed rollers for drawing said material from said supply reel, a pair of corrugated rollers in engagement with each other, said feed rollers feeding said material to said corrugated rollers, whereby said material is wound about one of said corrugated rollers, a movable arm on which the other of said corrugated rollers is mounted, means for moving said other roller out of engagement with said first corrugated roller, means for stripping the ring of material from said first roller, and a knife moving intermittently to cut the material between said feed rollers and said corrugated rollers.
11. In combination, a pair of co-operating winding rollers, means for feeding a strip of packing material thereto, means for separating said rollers at intervals, means for stripping a ring of wound material from one of said rollers, a turret having openings therein located to receive said wound material, means for rotating said turret intermittently, and means for compressing said material while held by said turret.
12. A device of the class described comprising means for winding a ribbon of metal foil into the form of a ring, means for corrugating the successive turns of said foil, and means for compressing said rings longitudinally to cause irregular disposition of the material therein in a direction at right angles to said corrugations.
13. The method of manufacturing metallic packing which consists in winding a strip of metal tape into a continuous corrugated ring and thereafter compressing said ring to bend the layers thereof back and forth in directions substantially at right angles to said corrugations.

In testimony whereof, I have subscribed my name.

MARTIN M. CODY.
